HAIR CURLING CLAMP

Antonino Mazzola, Beaumont, Tex.

Application July 10, 1934, Serial No. 734,502

2 Claims. (Cl. 132—33)

This invention relates to new and useful improvements in hair curling clamps.

The invention has to do with clamps used in waving or curling hair upon a roller carried by said clamp, whereby the hair may be engaged by the clamps and the roller thus held in place.

One object of the invention is to provide an improved device having air channels or passages, whereby the natural flow of air through said passages will carry off the heat incident to the curling operation, thereby preventing injury to the scalp and eliminating the necessity of an auxiliary cooling means.

Another object of the invention is to provide a self cooling clamp which dissipates the steam generated from the curling medium to prevent burning of the scalp; thus, permitting said clamp to be positioned closer to the head, whereby the curl may be set closer to the scalp to curl a greater portion of the hair and form a larger wave.

A further object of the invention is to provide an improved hair curling clamp having clamping sleeves constituting conduits for air currents, arranged to be readily replaced upon becoming soiled, torn, or otherwise unusable.

A construction designed to carry out the invention will be hereinafter described, together with other features of the invention.

The invention will be more readily understood from a reading of the following specification and by reference to the accompanying drawing, in which an example of the invention is shown, and wherein:

Figure 1 is a perspective view of a clamp constructed in accordance with the invention.

Figure 2 is a transverse vertical sectional view taken on the line 2—2 of Figure 1.

Figure 3 is a plan view of the form shown in Figure 1.

Figure 4 is a side elevation of a clamp having a curling roller mounted thereon and showing strands of hair wound thereon.

Figure 5 is a perspective view showing another form of the clamp.

Figure 6 is a transverse vertical sectional view taken on the line 6—6 of Figure 5.

Figure 7 is a transverse vertical sectional view taken on the line 7—7 of Figure 5, and

Figure 8 is a plan view of the form shown in Figure 5.

In the drawing the numeral 10 designates the frame of a hair curling clamp, which includes a pair of inverted channel shaped parallel clamping members or bars 11 and 12. For the purpose of more clearly describing the invention, the de-

vice is set forth as having a forward end and a rear end. The bar 11 is formed with an offset connecting arm 13 at its rear end. The other clamping bar 12 has its rear end pivotally mounted on the outer end of this arm by means of a screw 14, as is shown in Figures 1 and 3.

An open-ended jacket or sleeve 15 of rubber compound or any cushioning and insulating material suitable for the purpose, is slid over each bar 11 and 12 which, too, are open-ended. These sleeves extend substantially the entire length of the bars. It is pointed out (Figures 2, 6 and 7) that the bars, being channel shaped and covered by the sleeves 15, provide air passages 16. So, too, it is noted that the channels are relatively deep as compared to width thereof and that, being inverted, there is no metal except the two spaced edges of the channeled bars 11 and 12 overlying the part of the cushioning sleeve 15 that comes in contact with the scalp. Thus, it will be seen that with this structure the air is caused to circulate through the passages and carry off from the bottom of the clamp the heat which is used in curling the hair, thus preventing said heat from reaching the scalp and injuring the same.

Furthermore, it is obvious that a softer cushioning effect is had because of the space between the side walls of the bars which allows more yieldability of the material of the sleeve 15 where the contact with the scalp occurs.

The natural flow of air through the passages 16 makes unnecessary the use of any complicated or auxiliary cooling system or heat insulating means, as is required with the usual hair curling clamps. In placing a wave in the hair, the hair is dampened, wound upon a curler roller, and heat is applied to the hair on the roller. Care has to be taken to prevent the heat from injuring the scalp and particularly to prevent the steam, which is generated from the heating of the dampened hair, contacting the scalp. As the bottoms of the sleeves will be close to the head (Figure 4), the air circulating through the passages will cool the bottom of the clamp and carry off the heat and steam, while at the same time, there being only edge contact of the side walls of the channeled bars 11 and 12 with that portion of the sleeves 15 that comes in contact with the scalp, there is no uncomfortable or injurious heat transmission through said scalp contacting portions of the sleeve.

The sleeves, when made of a yieldable material, form a flexible covering for the bars; and the channels opening on the bottoms of the bars, soft

pads for the head are thus provided. The hair is firmly gripped between the bars, so that the steam resulting from heating the dampered hair will not pass down between the sleeves and come into contact with the scalp. It is pointed out that the clamp is so constructed that not only may it be positioned closer to the scalp without injury thereto, but also more of the hair may be curled, thereby setting the wave in the hair closer to the scalp, which forms a longer wave.

An upright bracket 17 having a rectangular recessed upper portion is mounted on the forward end of the bar 12 and has a pin or keeper 18 thereon. The forward end of the bar 11 is provided with a swinging latch 19, which is pivoted thereto and is provided with a downwardly extending bill 20 for engaging the keeper 18. The bill is provided with a plurality of notches 21 on its underside for engagement with the keeper, whereby the bars will be held in close proximity and will be substantially parallel with each other. Thus, variations in the pressure exerted on the hair by the bars 11 and 12 will be obtained and this variation in pressure is provided for the clamping of different thicknesses of hair between said bars.

An upright bracket 22 is mounted on the rear of the connecting arm 13. A swinging hook 23 is pivoted to the upper end of the bracket. As is shown in Figure 4, a hair curling roller 24 of the type now in common use is provided with the usual hinged tongue 25, a squared shaft extension 26 of an internal ratchet (not shown) on one end, and a trunnion 27 on the other end. The ends of the hair are clamped beneath the tongue and the hair is then wound on the roller in the usual manner. The clamp is then positioned and fastened, as shown in Figure 4, to engage the hair under the roller. The ratchet shaft extension 26 is next set into the bracket 17 and the trunnion 27 is engaged in the bracket 22 where it is confined by the hook 23. The hair on the roller is then tightened in the usual manner.

In Figures 5, 6, 7 and 8, I have shown a slightly different form. In place of the screw 14, I provide a stud 28 on the rear end of the bar 11' and a hook 29 on the rear end of the bar 12'. The stud is so constructed that the hook 29 cannot be disengaged therefrom except when the bar 12' is swung outwardly to its furthermost position. A hook 23' is mounted on the upper portion of a bracket 22' and swings to engage over the trunnion 27 of the roller 24. On the forward end of the bars a swinging latch 19' similar to the latch 19 is pivoted to a bracket 17' on the bar 12'.

In the form shown in Figures 1, 2 and 3, the screw 14 and the latch 19 are removed to replace the sleeves. The sleeve on the bar 12 may then be slipped off the rear end and the sleeve on the bar 11 may be slipped off the front end. The sleeves have to be replaced as they become torn, soiled and otherwise unuseable.

In the form shown in Figures 5, 6, 7 and 8, it is only necessary to swing the bar 12' to its outermost position and disengage the hook 29 from the stud 28, whereby the sleeves may be easily slipped off or on the bars.

The description which has been given recites more or less detail of a particular embodiment of the invention, which is set forth as new and useful; however, I desire it understood that the invention is not limited to such exact details of construction, because it is manifest that changes and modifications may be made, within the scope of the appended claims, without departing from the spirit of the invention.

It is pointed out that in operating the device, some operators may use it as described; while others may position the clamp on the hair first, then secure the ends of the hair under the tongue and wind the same on the roller in the usual manner.

What I claim and desire to secure by Letters Patent is:

1. A hair curling clamp comprising, a pair of elongated hair clamping bars, each of said bars having an air passage extending therethrough, said bars being hinged at one end, a swinging latch for fastening said bars in a clamping relation, and flexible sleeves surrounding said bars intermediate their ends, said bars being so constructed that they may be readily disengaged, whereby said sleeves may be removed, said latch having means, whereby different thicknesses of hair may be clamped, and upright brackets on the bars for supporting a curl roller therewith.

2. A hair curling clamp including, a cooperative pair of rigid open-ended channel bars having their open sides directed towards the scalp and closed adjacent sides between which the hair is clamped, flexible tubes of cushioning and insulating material enclosing the bars, whereby air-backed cushions are provided for contact with the scalp and rigidly supported flexible surfaces are provided for clamping the hair, the tubes being open at their ends and unobstructed throughout their length to permit a free natural flow of air currents through said channels and tubes, and means for fastening the bars together in their clamping relation.

ANTONINO MAZZOLA.
